ART OF CRACKING HYDROCARBONS

Eugene C. Herthel and Thomas De Colon Tiffet,
Chicago, Ill., assignors to Sinclair Refining
Company, New York, N. Y., a corporation of
Maine

Application November 1, 1929, Serial No. 403,985

3 Claims. (Cl. 196—48)

This invention relates to improvements in the manufacture of lower boiling hydrocarbon oils, such as gasoline and gasoline-containing distillates, from higher boiling hydrocarbon oils, such as gas oil, fuel oil and topped crude oil, by distillation of the higher boiling oils under super-atmospheric pressure.

This invention is, in one aspect, a further improvement with respect to the process described and claimed in Letters Patent No. 1,677,772, granted to the Sinclair Refining Company, July 17, 1928, on our application.

In carrying out the present invention, higher boiling oil is forced through a heating zone in heat exchange with heating gases, such as the hot products of combustion from a furnace in which fuel is burned, by which it is heated to a cracking temperature and is then discharged into a primary vaporizing zone from which vapors of the cracked oil are taken off under super-atmospheric pressure; these vapors of the cracked oil are subjected to a refluxing operation in which components of the vapors higher boiling than suitable as components of the desired product are condensed and this reflux condensate is returned to the heating zone and forced therethrough; unvaporized oil collecting in the primary vaporizing zone is discharged therefrom into a secondary vaporizing zone from which vapors are taken off under a pressure lower than that prevailing in the primary vaporizing zone, this further vaporization being effected largely or entirely by this reduction of pressure, these vapors are subjected to a condensing operation, in which however only part of the vapors may be condensed, in which components higher boiling than suitable as components of the desired product are condensed and this condensate is also returned to the heating zone and forced therethrough.

According to the present invention, the reflux condensate from the primary vaporizing zone is passed, in the heating zone, in heat exchange with the heating gases while the latter are at highest temperature and before they pass in heat exchange with the condensate from the secondary vaporizing zone; and the condensate from the secondary vaporizing zone is passed, in the heating zone, in heat exchange with the heating gases after the latter are at a temperature reduced by the first heat exchange; and residual unvaporized oil containing pitch constituents produced in the cracking operation is not permitted again to pass through the heating zone from either the primary or the secondary

vaporizing zone. The reflux condensate from the primary vaporizing zone produced from vapors taken off under high pressure is relatively refractory towards further cracking as compared to the condensate from the secondary vaporizing zone produced from vapors taken off under lower pressure; the more refractory oil is thus subjected to the more severe cracking conditions advantageous to its further cracking at the same time that it is used to temper the heating gases before the latter pass in heat exchange with the less refractory oil minimizing any tendency toward overheating or overcracking of the latter. Raw oil may be supplied to the heating zone with the condensate from the secondary vaporizing zone, or relatively refractory raw oil may be supplied to the heating zone with the reflux condensate from the primary vaporizing zone. If several raw stocks are supplied to the operation, relatively less refractory raw oil is advantageously supplied to the heating zone with the condensate from the secondary vaporizing zone and relatively more refractory raw oil is advantageously supplied to the heating zone with the reflux condensate from the primary vaporizing zone.

The invention will be further described in connection with the accompanying drawings which illustrate, diagrammatically and conveniently, several forms of apparatus adapted for carrying out the invention, but it will be understood that the process of the invention can be carried out in other and different apparatus.

Referring to Fig. 1, the hot oil products from the heating zone are discharged into the primary drum 6 through connection 7, vapors are taken off from drum 6 through connection 8 to reflux condenser 9, reflux condensate from condenser 9 is supplied to tank 10 through connection 11, residual oil is discharged from drum 6 through connection 12, including pressure reducing valve 13 into the secondary drum 14, vapors are taken off from drum 14 through connection 15 to condenser, or partial condenser, 16, condensate from condenser 16 is supplied to tank 17 through connection 18, and vapors remaining uncondensed are taken off from condenser 9, or from condensers 9 and 16, to final condenser 19, or final condensers 19 and 20, respectively, and there condensed to form a distillate product. The heating furnace illustrated, in Fig. 1, comprises a pair of single pass heaters 21 and 22 connected in series and arranged in the furnace 39 so that the heating gases from the firebox pass first over the heater 21 and then over the

heater 22 with a connection 23 for supplying oil to the heater 21 and a connection 24 for supplying oil to the connection between the heaters 21 and 22. Oil from tank 10 is supplied to connection 23 by means of pump 25, and oil from tank 17 is supplied to connection 24 by means of pump 26.

Raw oil may be used as a condensing medium in the condensers 9 and 16. For example, raw oil 10 may be passed successively through the condensers 9 and 16 in indirect heat exchanging relation with the vapors therein by means of pump 27 and connections 28, 29 and 30 and then introduced either into tank 10 or tank 17 or both 15 tanks 10 and 17 through connections 31 and 32. Raw oil may be supplied directly to tank 10 through connection 33 and to tank 17 through connection 34. Excess condensate mixture may also be discharged through connections 33 and 34. 20 Pressure in drum 6 may be maintained and regulated by means of valve 35 or valve 36 or by means of suitable valves beyond the condenser 19. Pressure in drum 14 may be regulated by means of valve 37 or valve 38 or by means of 25 suitable valves beyond the condenser 20.

Drum 6 is advantageously externally unheated, being heated internally only by the heat of the hot oil products discharged through connection 7. It may, however, be mildly heated externally 30 by means of furnace 40. It is with advantage lagged or thermally insulated to minimize heat loss. Drum 14 is advantageously externally unheated, and is with advantage lagged or thermally insulated to minimize heat loss. Connections 12, 11 and 23, and 18 and 24 and tanks 10 35 and 17 are also with advantage lagged or thermally insulated to minimize heat loss.

In the manufacture of gasoline, for example, the furnace 39 may be operated so that the hot 40 oil products discharged from the heaters 21 and 22 are at a temperature as discharged through connection 7 in the general range of 800-1200° F., the drum 6 may be maintained under a pressure in the neighborhood of 100-300 pounds per 45 square inch and the drum 14 may be maintained under a pressure in the neighborhood of 0-50 pounds per square inch. Raw oil, gas oil for example, may be supplied entirely to tank 17, or several raw oils may be supplied to the tanks 10 50 and 17 according to the extent to which they are refractory to the cracking conditions maintained in the heaters 21 and 22, light gas oil for example may be supplied to tank 10 and heavy gas oil for example to tank 17. Vaporization in drum 55 14 may be carried only far enough to leave a flux or heavy residue which can be removed as a liquid or it may be carried so far that only coke or a cokey mass remains.

Instead of connecting the heaters 21 and 22 in 60 series, as illustrated in Fig. 1, each of these heaters may be arranged to discharge directly into drum 6 through connection 7, as illustrated in Fig. 2, in which the same parts have the same reference numeral as in Fig. 1 with the letter *a* appended.

65 A condenser providing for direct heat exchange between the condensing medium and the vapors may be substituted for the condenser 16 illustrated in Fig. 1. As illustrated in Fig. 3, in which the same parts bear the same reference numeral 70 as in Fig. 1 with the letter *b* appended, raw oil, gas oil for example, may be introduced directly into condenser 16*b* through connection 41 and supplied to the tank 17 in admixture with the condensate from this condenser through connection 18*b*.

75 The single reflux condenser 9 illustrated in Fig.

1 may be replaced by a pair of reflux condensers 9'*c* and 9*c*, as illustrated in Fig. 4, in which the same parts bear the same reference numeral as in Fig. 1 with the letter *c* appended, reflux condensate from the first 9'*c* being returned directly to drum 6*c* through connection 42 and reflux condensate from the second 9*c* being supplied to the heater over which the heating gases first pass through connection 11*c*. It will be apparent that connection 42 must include a pump if a 10 higher pressure is maintained in the drum 6*c* than in the condenser 9'*c*.

The single reflux condenser 9 illustrated in Fig. 1 may be replaced by a pair of reflux condensers 9*d* and 9'*d*, in which the same parts bear the same reference numeral as in Fig. 1 with the letter *d* appended, reflux condensate from both the condensers 9*d* and 9'*d* being supplied to the heater over which the heating gases first pass through connection 11*d*, raw oil eventually supplied to one of the heaters being used as a condensing medium in the condenser 9*d*, and an easily cracked raw oil being used as a condensing medium in the condenser 9'*d* and then introduced directly into the drum 6*d* through connection 43 by means of pump 44. Reflux condensers 9*d* and 9'*d* may also be reversed; that is, an easily cracked raw oil may be used as a condensing medium in the condenser through which the vapors from the drum 6*d* first pass and then introduced directly into the drum 6*d* through connection 43 and raw oil eventually supplied to one of the heaters may be used as a condensing medium in the condenser through which the vapors next pass; and with this arrangement both reflux condensers may be of the general type (illustrated in Fig. 3) providing for direct heat exchange between the condensing medium and the vapors, the condensate from the first reflux condenser then being returned directly to drum 30 35 40 45 50 55 6*d* (as in the apparatus illustrated in Fig. 4) in admixture with the raw oil condensing medium introduced into this reflux condenser.

We claim:

1. In cracking hydrocarbon oils, the improvement which comprises forcing high boiling oil through a heating zone and heating it to a cracking temperature therein by heat exchange with heating gases and discharging the hot oil products from the heating zone into a primary vaporizing zone, taking off vapors from this primary vaporizing zone under superatmospheric pressure and subjecting them to reflux condensation, discharging unvaporized oil from the primary vaporizing zone into a secondary vaporizing zone maintained under a pressure lower than that prevailing in the primary vaporizing zone, taking off vapors from this secondary vaporizing zone and subjecting them to condensation, and, in the heating zone, passing condensate from said reflux condensation in heat exchange with the heating gases before the latter pass in heat exchange with condensate from said condensation and passing condensate from said condensation in heat exchange with the heating gases after the latter have been tempered by the first heat exchange without permitting any unvaporized oil containing pitch constituents produced in the cracking operation again to pass through the heating zone from either of the vaporizing zones.

2. In cracking hydrocarbon oils, the improvement which comprises forcing high boiling oil through a heating zone and heating it to a cracking temperature therein by heat exchange with heating gases and discharging the hot oil prod-

ucts from the heating zone into a primary vaporizing zone, taking off vapors from this primary vaporizing zone under superatmospheric pressure and subjecting them to reflux condensation, discharging unvaporized oil from the primary vaporizing zone into a secondary vaporizing zone maintained under a pressure lower than that prevailing in the primary vaporizing zone, taking off vapors from this secondary vaporizing zone and subjecting them to condensation, and, in the heating zone, passing condensate from said reflux condensation in heat exchange with the heating gases before the latter pass in heat exchange with condensate from said condensation and passing condensate from said condensation in heat exchange with the heating gases after the latter have been tempered by the first heat exchange without permitting any unvaporized oil containing pitch constituents produced in the cracking operation again to pass through the heating zone from either of the vaporizing zones, and supplying relatively less refractory raw oil to the heating zone with the condensate from said condensation and supplying relatively more refractory raw oil to the heating zone with the condensate from said reflux condensation.

through a heating zone and heating it to a cracking temperature therein by heat exchange with heating gases and discharging the hot oil products from the heating zone into a primary vaporizing zone, taking off vapors from this primary vaporizing zone under superatmospheric pressure and subjecting them to reflux condensation, discharging unvaporized oil from the primary vaporizing zone into a secondary vaporizing zone maintained under a lower pressure than that prevailing in the primary vaporizing zone, taking off vapors from this secondary vaporizing zone and subjecting them to condensation, and, in the heating zone, passing condensate from said reflux condensation in heat exchange with the heating gases before the latter pass in heat exchange with condensate from said condensation and passing condensate from said condensation in admixture with the thus heated condensate from said reflux condensation in heat exchange with the heating gases after the latter have been tempered by the first heat exchange without permitting any unvaporized oil containing pitch constituents produced in the cracking operation again to pass through the heating zone from either of the vaporizing zones. 5 10 15 20 25

3. In cracking hydrocarbon oils, the improvement which comprises forcing high boiling oil
